(57) **CLAIM**

The ornamental design for an air grate for raised floors, as shown and described.

DESCRIPTION

FIG. 1 is a perspective view of an air grate for raised floors;

FIG. 2 is a top view thereof;

FIG. 3 is a bottom view thereof;

FIG. 4 is a side view thereof, the opposite side being the same;

FIG. 5 is an adjacent side view thereof, the opposite side being the same;

FIG. 6 is a perspective view of another embodiment of an air grate for raised floors;

FIG. 7 is a top view thereof;

FIG. 8 is a bottom view thereof;

FIG. 9 is a side view thereof, the opposite side being the same; and,

FIG. 10 is an adjacent side view thereof, the opposite side being the same.

The broken line showing of the surrounding floor structure is included for the purpose of illustrating use and environment and forms no part of the claimed design.

1 Claim, 8 Drawing Sheets
